SHOE AND METHOD OF MAKING THE SAME

Karl Engel, Lynn, Mass., assignor to United Shoe
Machinery Corporation, Paterson, N. J., a cor-
poration of New Jersey

Application September 12, 1933, Serial No. 689,148

11 Claims. (Cl. 12—142)

This invention relates to shoes and the art of shoemaking and is herein illustrated in its application to the manufacture of pre-welted shoes, that is, shoes in which the welt is attached to the upper prior to the lasting of the upper. As herein illustrated, such shoes may be provided with a welt which extends around the heel, as well as the forepart, of the shoe.

In pre-welted shoes heretofore manufactured, the welt is united to the upper by a seam which passes also through the lining, an insole or slip sole being secured to the inner surface of the shoe bottom in order to cover the seam and thereby to promote the comfort and improve the appearance of the shoe. The insole or slip sole is thin and tends to become misplaced as the shoe is worn, and often becomes a source of discomfort to the wearer.

Objects of the present invention are to provide a comfortable and attractive pre-welted shoe without using a slip sole or insole while retaining all of the advantages of pre-welted shoes heretofore manufactured and reducing the cost of manufacturing such shoes.

Features of the invention consist in the provision in a pre-welted shoe, the welt of which is secured to the upper by fastenings extending upwardly into the shoe substantially to the plane of the inner surface of the shoe bottom, of a lining arranged to overlie said fastenings in order to provide a shoe bottom, the foot-contacting surface of which has no exposed fastenings. Preferably, and in accordance with another feature of the invention, the lining which overlies said fastenings is arranged to extend downwardly of the shoe bottom between the edge face of a filler and the adjacent edge faces of the welt and upper, the margin of said lining extending inwardly of the shoe between the adjacent surfaces of the filler and an outsole. Preferably the lining is secured between the filler and the outsole by adhesive. As herein illustrated, the filler occupies the entire space enclosed by the adjacent edge faces of the welt and upper. Thus, it will be seen, a shoe bottom is provided the inner surface of which has no exposed stitches and presents a smooth and unbroken surface to the foot without the employment of a sock lining or innersole. Such a shoe possesses a great advantage over pre-welted shoes heretofore manufactured in that the inner surface of the shoe bottom consists largely of the grain surface of a leather filler the thickness of which is equal to the combined thicknesses of the welt and upper and obviously can not be crumpled or otherwise injured in the

course of wear, and, being entirely surrounded and retained in position by the welt, the filler can not be misplaced but will be held in position as long as the welt remains united to the outsole. The margin of the lining is preferably held between the filler and the outsole, for example, by cement, thereby providing a bond between the upper lining and the shoe bottom which tends to strengthen the shoe and to retain the shape of the shoe in the course of wear. Moreover, since the lining is not sewed to the upper, and its margin is beneath the filler, all stitches and the raw edges of welt and lining are concealed.

In one aspect thereof the invention comprises an improvement in methods of making pre-welted shoes provided with a filler and with a lining which is not secured to the welted margin of the upper, which method consists in lasting the adjacent edge faces of the welt and upper against the edge face of the filler with the lining disposed therebetween, lasting the margin of the lining to the filler, and securing said margin in lasted position, for example by adhesive. Preferably the filler is temporarily attached to the last bottom, the location of its edge face determining the extent to which the pre-welted upper is wiped or pulled over the last bottom. The unattached margin of the lining presents no obstacle to the lasting of the shoe, the upper being assembled upon the last, as usual, and then wiped or pulled over the last bottom. In working the upper over the last any wrinkles that may have formed in the lining may be removed by separately pulling the portion of the lining which extends beyond the upper.

The various features and aspects of the invention will appear more fully from the following description when read in connection with the accompanying drawing and will be pointed out in the appended claims.

In the drawing,

Fig. 1 is a perspective view of a pre-welted shoe embodying the features of the present invention, the toe portion of the shoe being broken away and the heel end of the filler being drawn forwardly away from the shoe bottom; and

Fig. 2 is a perspective view of the toe end of a pre-welted shoe in the course of manufacture, the margin of the lining at one side of the shoe being laid over upon and cemented to the filler while the margin around the toe and at the opposite side of the shoe remains upstanding.

Referring to Fig. 1, the illustrated shoe comprises an upper 10 which has stitched to its upper edge a lining 12 which is formed to extend beyond

the everlasting margin of the upper. A welt 14 is secured to the everlasting margin of the upper by stitches 16 which pass through the welt and upper but do not extend through the lining. A 5 filler 18, preferably consisting of a piece of grain leather with its grain surface uppermost, is formed and arranged to fill the space enclosed by the welt and the margin of the upper and is retained in position in the finished shoe by the 10 welt. The lining 12 is provided with a wide margin 24 which, in the illustrated shoe, extends from the heel breast line forwardly of the shoe to the point where the curvature about the toe end of the shoe commences, the width of said margin 15 about the toe end of the shoe being reduced in order to obviate the necessity of pinking or pleating the margin of the lining about the toe. The margin 24 of the lining is arranged between the filler 18 and the outsole 22 and secured in position, for example, by cement applied to the lining 20 and to the under surface of the filler. If desired, cement may also be applied to the edge face of the filler and the adjacent edge faces of the welt and upper in order to secure the margin of the 25 upper in the lining therebetween. Waterproof cement is preferable. Of the various waterproof cements pyroxylin cement has the advantage of providing a strong and enduring bond without impairing the flexibility of the shoe.

30 In the illustrated shoe, as a matter of convenience in manufacture, the lining about the heel end of the shoe is united to the upper and welt by the seam 16 and the lining is cut off even with the edge of the upper. A heel pad (not 35 shown) conceals the stitching 16 at the heel end of the shoe and prevents any discomfort which might be caused by the pressure of the heel of the wearer against the seam 16. If desired, however, the lining may be extended to form a margin 40 at the heel end of the shoe similar to the margin formed at the toe end of the shoe in which case the seam 16 would not extend through the lining at the heel end of the shoe and the heel pad could be eliminated.

45 The preferred method of making pre-welted shoes in accordance with the present invention consists in securing the filler 18 temporarily to the bottom of a last 26 (Fig. 2), providing the pre-welted upper 10 with a lining 12 the marginal portions of which at opposite sides of the shoe extend somewhat beyond the edge of the upper. The upper may be lasted in any known manner, the margin 24 of the lining preferably remaining upstanding during the lasting operation. While the upper is held in lasted position, for example, by wipers 28 of a bed lasting machine, adhesive, for example, pyroxylin cement, is applied to the margin of the filler 18 and the 50 margin 24 of the lining is then laid over upon the margin of the filler. If desired, however, adhesive may have been applied to the filler before mounting the filler on the last bottom in which case the lasting of the upper is followed 55 immediately by the overwiping of the margin of the lining upon the margin of the filler. A cemented outsole is then laid upon the shoe bottom in any known manner and stitched thereto. The pressure of the outsole against the shoe bottom in the sole laying operation serves to press the 60 margin 24 of the lining against the filler thereby producing a firm bond between the lining and the filler.

Having described my invention, what I claim as new and desire to secure by Letters Patent of 70 the United States is:

1. In a pre-welted shoe, the welt of which is secured to the upper by fastenings extending upwardly into the shoe substantially to the plane of the inner surface of the shoe bottom, a lining arranged to overlie said fastenings in order to provide a shoe bottom the foot contacting surface of which has no exposed fastenings. 5

2. In a pre-welted shoe provided with a filler and having its welt secured to the upper by fastenings extending upwardly into the shoe substantially to the plane of the inner surface of the shoe bottom, a lining arranged to overlie said fastenings and to extend downwardly of the shoe between the adjacent edge faces of the filler and the welt. 10

3. In a pre-welted shoe provided with a filler and having its welt secured to the upper by fastenings extending upwardly into the shoe substantially to the plane of the inner surface of the shoe bottom, a lining arranged to overlie said fastenings and to extend downwardly of the shoe between the adjacent edge faces of the filler and the welt and inwardly between the adjacent surfaces of the filler and the outsole. 15

4. In a pre-welted shoe provided with a filler and having its welt secured to the upper by fastenings extending upwardly into the shoe substantially to the plane of the inner surface of the shoe bottom, a lining arranged to overlie said fastenings and to extend downwardly of the shoe between the adjacent faces of the welt and filler to which it is secured by adhesive. 25

5. In a pre-welted shoe provided with a filler and having its welt secured to the upper by fastenings extending upwardly into the shoe substantially to the plane of the inner surface of the shoe bottom, a lining arranged to overlie said fastenings, to extend downwardly of the shoe between the adjacent faces of the filler and the welt, and to underlie the margin of the filler to 30 which it is adhesively secured. 35

6. In a pre-welted shoe provided with a filler of smaller area than the inner surface of the shoe bottom and having its edge face arranged substantially adjacent to the inner edge face of the welt, fastenings for securing the welt to the upper arranged to extend upwardly into the shoe substantially to the plane of the inner surface of the shoe bottom, and a lining arranged to overlie the marginal portion of the inner surface of the shoe bottom in order to cover said fastenings and arranged to extend downwardly of the shoe between the adjacent faces of the welt and filler. 45

7. That improvement in methods of making pre-welted shoes provided with a filler and with a lining which is not secured to the welted margin of the upper, which comprises lasting the adjacent edge faces of the welt and upper 50 against the edge face of the filler with the lining disposed therebetween, lasting the margin of the lining to the filler, and securing said margin in lasted position. 60

8. That improvement in methods of making pre-welted shoes provided with a filler of smaller area than the inner surface of the shoe bottom and with a lining which extends beyond and is not secured to the welted margin of the upper, which comprises lasting the margins of the upper 65 and lining over the marginal portion of the last bottom thereby bringing the adjacent edge faces of the welt and upper against the edge face of the filler with the lining disposed therebetween 70 and lasting the margin of the lining to the filler. 75

9. That improvement in methods of making pre-welted shoes provided with a lining which is not secured to the welted margin of the upper which comprises lasting the welted margin of the upper, together with the lining, over the margin of the last bottom and thereafter securing the margin of the lining to the shoe bottom.
10. That improvement in methods of making pre-welted shoes provided with a lining which extends beyond and is not secured to the welted margin of the upper which comprises lasting the welted margin of the upper, together with the lining, over and upon the margin of the last bottom and thereafter securing the extended margin of the lining between a filler and an ¹⁰ outsole.
